UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

BUFFER MECHANISM FOR DIAPHRAGM FACE PLATES.

Application filed June 22, 1926. Serial No. 117,848.

Upper buffer mechanisms are used to keep the diaphragm face plates of adjacent passenger train cars in contact under all service conditions. The face plate must be permitted to move longitudinally, laterally and/or obliquely relative to its normal position on the car. It must be permitted to move laterally of itself (i. e. longitudinally of the car) to accommodate the draft gear movements and must move longitudinally of itself so that when one car swings more than its adjacent car the friction between the face plates will not tear either of them from their attachments. Furthermore, the face plate must move obliquely when the cars are moving on a curved track. The face plate may, of course, make all of these movements consecutively or simultaneously.

My invention relates to devices which 20 yieldingly permit the face plate to make such movements and which have a tendency to return the face plate to its normal position and which do return it to such normal position when permitted to do so.

25 An object of the invention is to provide such a device which is simple and economic to manufacture and apply and which can be installed, inspected, repaired or replaced without entering the car or removing any 30 part thereof, not even the diaphragm of its face plate. Furthermore, the device is noiseless because all the parts are under pressure contact.

In the drawings:

35 Fig. 1 shows a typical application of my device to a railway car.

Figs. 2, 3, 4 and 5 are diagrams showing the device in various service conditions.

40 Fig. 6 is a detail of the resilient member.

Fig. 7 is a detail of the car end attachment.

Fig. 8 is a detail of the face plate attachment.

45 Fig. 9 is a detail of a modified form of the face plate attachment.

Figs. 10, 11, 12 and 13 are modified forms of springs.

The usual parts of a railway passenger train car are shown, such as the end wall 1, diaphragm 2, and diaphragm face plate, 3.

50 My device comprises two resilient members 4, preferably duplicates, each of which

has one end (40) rigidly secured to the car end element 1 (or face plate element) and its opposite end 42 pivotally secured to the

other element. I have shown and described a form wherein the outer end of each spring is pivotally secured to the end wall by the brackets 5 which are positioned equi-distant from the center of the car and the inner end 60 of each spring is rigidly secured to the face plate by a device 6 which is positioned at the middle of the face plate.

Fig. 1 shows a typical application of my device to a railway car, while Figs. 2-5, inclusive, are diagrams showing its action under service conditions. Fig. 2 shows the associated parts in normal position, while Fig. 3 shows them under maximum compression forcing the opposite ends of the spring 70 toward each other or foreshortening it. Fig. 4 shows the device when the face plate has moved longitudinally (or sidewise of the car), wherein the opposite ends of one spring 7 are forced toward each other and the ends 75 of the other spring 8 are pulled apart. Fig. 5 shows the face plate moved obliquely wherein the springs have been foreshortened as the distance between 9 and 10 and 11 and 12, respectively, is less than when in normal 80 position, as shown in Fig. 2. A stop 60 prevents the pivotal connections of the inner ends of the springs from going nearer to the end wall than the pivotal connections of the outer ends (or beyond dead center.) If such 85 a relation of parts should exist the device would not return to normal position.

The device may be applied to a car having an apiced diaphragm face plate with its middle portion higher than the place of the attachment of the springs to the end wall.

90 The resilient member 4 must be capable of yieldingly foreshortening its length and also be capable of yieldingly increasing its length and then returning to its normal length under either condition by its own inherent power. Figs. 4, 10, 11, 12 and 13 show various types of resilient members which have this capacity. Fig. 4 shows a rectangular bar slightly bowed, while Figs. 10 and 12 are 95 also rectangular bars bent to form an ogee or reverse curve. Fig. 13 shows a semi-elliptic spring with the auxiliary leaves on the inside of the curvature so as to resist the further deflection. Fig. 11 shows a member 100 having a coil (or coils) to resist further deflection.

105 The resilient members are preferably bowed or given an initial deflection to assure that under further stress they will deflect 110

in the desired direction. This is desirable, no matter what kind of spring is used. Furthermore, the bow makes an easier acting spring by giving it an initial eccentricity.

5 The spring must not be restricted in its action by contact with any part of the car, such as the face plate at 15 or 16 (or the car if the springs are bowed the other way.) In the construction illustrated the effective 10 ends of the springs adjacent the face plate are spaced apart from the face plate sufficiently to permit the spring to deflect under the maximum service conditions without interference with the face plate. The two 15 bowed springs are interposed between the car end element 1 and the diaphragm face plate element 3, and broadly expressed, the effective end of the spring adjacent the element toward which the spring is bowed must be 20 spaced apart from that element to assure clearance for the proper action of the bowed spring. The "effective end" (20) is that portion of the spring where the deflection starts and is not necessarily its extremity.

25 The pivoted attachment, with the abutment, is disclosed and specifically claimed in application for patent, Serial No. 117,847, June 22, 1926. Briefly, however, the bracket 5 has oppositely disposed perforated 30 walls 22-23 and the resilient member 4 is formed with an eye 25 at the pivoted end and a bolt 24 passes through the perforations 21 and the eye. The size of the eye being sufficiently larger than the size of the bolt to 35 permit the member to engage the abutment when under stress. Fig. 9 shows a bracket having elongated perforations 21 which could be used to assure the end of the spring engaging the abutment, and, furthermore, to 40 permit the spring 8 to move a certain distance before stressed, or an elongated eye could be used on the spring for the same purpose.

45 There are certain advantages obtained by rigidly attaching one end of such a resilient member to its adjacent car part, one of which is to put a lateral stress (in addition to the longitudinal stress) upon the resilient member, thereby increasing the forces in the 50 spring tending to return it to its normal position. This is especially true when the face plate is in an oblique position.

55 In the form illustrated the resilient member 4 is attached to the face plate 3 by a device 6 having oppositely disposed perforated walls 50 and also a vertical abutment 52 and a retaining wall 53 (shown as semi-circular.) The resilient member 4 is formed at this end with a lateral auxiliary extension 54, which 60 in assembled position, owing to an initial compression of the spring, bears against the abutment 52. The bolt 24 passes through the perforations holding the spring between it and the retaining wall 53. When the face 65 plate moves toward the car the angle 55 be-

tween the main portion of the spring and its lateral extension 54 is decreased, thus causing a force which tends to deflect the spring in addition to its foreshortening. It is preferable to provide a curved connection 56 between the main portion and the lateral portion of the spring to reduce breakages at this point. This spring is made so that upon assembly it is necessary to slightly decrease the angular relation between the main and auxiliary part of the spring. When the face plate moves toward the side of the car (see Fig. 4) the angular relation 55 of these parts is decreased on the left spring 7 and increased on the right spring 8. When the face plate assumes an oblique position (see Fig. 5) this angular relation is increased on the right spring 57 and decreased on the left spring 58 (or vice versa.) Any changing of this angular relation tends to return the spring (and face plate) to its normal position. This device 6 may be formed to accommodate both springs, as shown in the figures.

Fig. 7 is an enlarged view of the attachment of the spring (or springs) to the face plate.

The spring members are easily removed by simply taking out the bolts at the opposite ends of the particular spring without disturbing the other spring.

The springs are made so that it is necessary to slightly shorten their length (by deflecting them) in order to install them which causes the parts to be in pressure contact. This prevents rattling and noise which is desirable in sleeping cars and when the particular device is on the rear end of the last car, or when the car is coupled to a car not 100 equipped with a face plate.

I claim:

1. In a railway car; the combination of an end wall element, a diaphragm face plate element, and two resilient members, each of said members having one of its ends rigidly secured to one of said elements and its opposite end pivotally secured to the other of said elements.

2. In a railway car; the combination of an end wall, a diaphragm face plate, and two resilient members, each of said members having its inner end rigidly secured to the said face plate and its outer end pivotally secured to the said end wall.

3. In a railway car; the combination of an end wall element, a diaphragm face plate element, and two bowed spring members, each of said members having one of its ends rigidly secured to one of said elements, and its opposite end pivotally secured to the other of said elements.

4. In an upper buffer mechanism for railway passenger train cars, a connection between a resilient member and a part of the car, said connection comprising a bracket

having an abutment, a resilient member having a lateral extension engaging said abutment, and removable means to retain the parts in said position.

5. In a railway car; the combination of an end wall, a diaphragm face plate, two spaced apart brackets secured to the end

wall, a bracket secured to the middle of the face plate, and two resilient members, each end of each member attached to one of said brackets, one end of each member having a lateral extension engaging an abutment on its adjacent bracket.

ARTHUR E. SMALL.
